US0D1096816S

(12) **United States Design Patent** (10) Patent No.: **US D1,096,816 S**
Doty et al. (45) Date of Patent: ** Oct. 7, 2025

(54) **DISPLAY SCREEN OR PORTION THEREOF WITH A GRAPHICAL USER INTERFACE**

(71) Applicant: **Snap Inc.**, Santa Monica, CA (US)

(72) Inventors: **Devin Doty**, Brooklyn, NY (US); **Ian Anthony Wehrman**, Venice, CA (US)

(73) Assignee: **Snap Inc.**, Santa Monica, CA (US)

(**) Term: **15 Years**

(21) Appl. No.: **29/992,886**

(22) Filed: **Mar. 11, 2025**

Related U.S. Application Data

(62) Division of application No. 29/784,445, filed on May 19, 2021.

(57) **CLAIM**

The ornamental design for a display screen or portion thereof with a graphical user interface, as shown and described.

DESCRIPTION

The FIGURE is a front view of a display screen or portion thereof with a graphical user interface, showing our new design.

The broken lines illustrate the display screen, and the broken lines form no part of the claimed design.

1 Claim, 1 Drawing Sheet
